GOBLET

Lester A. Roden, Brooklyn, N. Y.

Application June 6, 1950, Serial No. 10,385

Term of patent 3½ years

(Cl. D36—8)

To all whom it may concern:

Be it known that I, Lester A. Roden, a citizen of the United States, residing at Brooklyn, State of New York, have invented a new, original, and ornamental Design for a Goblet, of which the following is a specification, reference being had to the accompanying drawing, forming a part hereof.

Fig. 1 is a side elevational view of a goblet showing my new design; and

Fig. 2 is a top plan view thereof.

I claim:

The ornamental design for a goblet as shown.

LESTER A. RODEN.
